SUSPENDERS

Henry L. Jackson, White Plains, N. Y.

Application September 9, 1944, Serial No. 553,408

4 Claims. (Cl. 2—325)

(Granted under the act of March 3, 1883, as amended April 30, 1928; 370 O. G. 757)

1

The invention described herein, if patented may be manufactured and used by or for the Government for governmental purposes, without the payment to me of any royalty thereon.

The present invention relates to garment supporting devices and more particularly has reference to suspenders made entirely of fabric and not including any buckles or clamps for adjusting the size of the suspenders.

I am well aware that numerous attempts have heretofore been made to devise suspenders which eliminated the employment of metallic buckles or clasps for the usual practices. These prior devices, however, have not proven entirely satisfactory. For example, these constructions have been relatively complex in structural detail which, of necessity, increased materially the cost of manufacture. Also, the means whereby adjustment of size is accomplished has not been of very sturdy or substantial construction with the attendant disadvantage of frequent breaking of the tab supporting member.

Accordingly, one important object of the present invention is to overcome the disadvantages now inherent in this art.

Another object of my invention is to provide a garment supporting device which is simple both in construction and operation, and which can be cheaply and easily manufactured.

Yet another object of this invention is to provide a garment supporting device which is made entirely of fabric material and which does not utilize buckles or clamps for effecting size adjustments.

A further object of my invention is to provide a garment supporting device with a double loop arrangement intermediate the shoulder straps and the rear button carrying member to afford flexibility of movement and absorb the strain imposed normally upon the rear button carrying member.

Still a further object of the present invention is to provide a novel adjusting construction for the button tab strap which does not employ the usual clasps or buckles.

To achieve the above, and other important objects, this invention generally embraces the idea of attaching to the front free edges of the shoulder straps, layers of fabric secured together, preferably by weaving, in such a manner as to provide a plurality of vertically spaced openings extending therethrough. A button tab strap is adapted to pass through any one of the openings and by the proper selection, the length of the suspenders may be readily adjusted. Suitably af-

2

fixed to the opposite free edges of the shoulder straps are loop members interconnected as to afford a slidable loop structure. Intermediate the slidable loop members and the rear button engaging tabs are resilient inserts for accomplishing the usual results.

By virtue of this construction, I provide a garment supporting device wherein the vertical adjustment of the device may be achieved without the use of metallic buckles or clasps. Moreover, the slidable loop arrangement in the rear will compensate for most of the strain subjected normally upon the resilient inserts, thereby increasing materially the life of the supporting device.

15 Various other objects and advantages of this invention will appear more fully hereinafter. It is to be understood that the specific embodiment or embodiments shown are merely illustrative and, hence, the detailed description thereof is not to be taken as limiting the invention *per se*.

10 Referring to the drawing wherein like numerals indicate the same or similar parts:

Figure 1 is a composite perspective view, illustrating the principles of my inventive concept.

25 Figure 2 is a sectional view taken along the line 2—2 of Figure 1, looking in the direction of the arrows.

Figure 3 is an enlarged fragmental view of one of the front adjusting strips.

30 Figure 4 is a detailed fragmental view of another type of rear connection between the shoulder straps and the resilient inserts that may be employed.

In Figure 1, there is shown a pair of shoulder engaging straps designated 1. A strap extension 2 is attached to the lower front edge of each of the straps 1 by stitches 3. The strap extension 2 comprises an upper layer of woven fabric 4 and a lower layer 5 of the same material. The layers 4 and 5 are secured together, preferably by weaving, to form a plurality of vertically spaced openings or tunnels 6, extending transversely therethrough. A button tab strap 7, having button-holes 8 woven in each end thereof, is of such size and configuration that it may be passed through any one of the openings 6. It will be appreciated, therefore, that by placing the strap 7 in the proper opening 6, the length of the suspenders may be adjusted readily.

45 It will be noted from Figure 3 that the upper and lower edges of the opening are formed with at least four points of contact identified A, B, C and D for the strap 7. The points B and C are in a different horizontal plane from A and D thereby defining in effect opposed curved or arcu-

ate upper and lower edges. This arrangement gives a more sturdy structure and there is little danger of damaging the opening since the strain imposed by the strap is distributed evenly throughout the entire length of the opening.

In view of the fact that the openings are centrally constricted by opposed curved upper and lower symmetrically divergent walls, a button-tab strap being carried in a selected opening and supported by one of said defining walls, it is apparent that either end of the strap extension 2 can be attached to the lower edge of the shoulder strap 1, which of course is very important from the manufacturing angle.

A loop indicated 9 is sewn, as shown at 10, to the opposite edge of each of the shoulder straps 1. Each loop is formed with an outer strip 11 and an inner strip 12. To provide flexibility of movement, the outer strip of one loop extends over the outer strip of the other loop and the inner strip of the first-named loop is disposed between the outer and inner strips of the second-named loop. It is obvious, therefore, that these interlocking loops provide a very flexible connection and have a wide latitude of movement with respect to each other.

A resilient strip or insert 14 is suitably secured at its upper edge to the lower edge of each loop 9, as indicated by the numeral 15, and the free edge of the insert is attached, as indicated at 16, to a rear button engaging tab 17. The button engaging tab 17 is made of fabric similar to the shoulder straps 1 and has woven therein a buttonhole 18.

In use, the shoulder straps 1 encircle the shoulders of the wearer, and the buttonholes 18 engage the rear buttons on the garment to be supported. After the wearer has determined the correct length of the suspenders, the button tab strap 7 is extended through the opening 6 which corresponds to this particular length, and the buttonholes 8 are engaged by the front garment buttons. By reason of the slideable loop construction 9, and the resilient inserts 14, the wearer may have freedom of movement, and there is relatively no strain imparted to the strips 14 due to the slideable loop structure 9.

It will be appreciated that my novel garment supporting device is highly desirable in that it is made entirely of fabric, thereby eliminating the utilization of buckles or clasps, heretofore resorted to for making the necessary size adjustments. Furthermore, the structure whereby the adjustment can be effected is very simple and, due to the manner in which it is made, there is little likelihood of injury.

In Figure 4, I have illustrated a modified type of construction for securing the shoulder straps 1' to the rear button tab 17. It will be observed that the lower edge of each of the straps 1' are sewn together as at 20. The upper edge of each of the resilient inserts 14' are sewn along their upper marginal edges to the straps 1', as shown at 21. To insure a more secure connection between the

shoulder straps and the inserts, I may provide additional rows of reinforcing stitches 22. In this particular form, I do not have as much flexibility of movement as that shown in Figure 1, since the slideable loops are omitted. However, this embodiment can be more cheaply and easily manufactured and the resilient insert 14' will provide sufficient flexibility for normal use.

It will be fully understood that the foregoing description and accompanying drawing cover only the general and preferred embodiment of the invention and that various changes in construction, proportion and arrangement of the elements may be made by those skilled in the art without departing from the spirit and scope of the invention as set forth in the appended claims.

Having thus described the invention and what I claim as novel and desire to be secured by Letters Patent is:

1. In a garment-supporting device, shoulder straps, button-engaging tabs carried by one end of said shoulder straps, a plurality of layers of woven fabric secured to the opposite end of said straps, transverse walls formed by weaving together portions of said layers so as to define an opening between said layers, and a button-tab strap carried in said opening and supported by one of said defining walls.

2. In a garment-supporting device, shoulder straps, button-engaging tabs carried by one end of said shoulder straps, a plurality of layers of woven fabric secured to the opposite end of said straps, transverse walls formed by weaving together portions of said layers so as to define a plurality of openings between said layers, and a button-tab strap carried in one of said openings and supported by one of said defining walls.

3. In a garment-supporting device, shoulder straps, button-engaging tabs carried by one end of said shoulder straps, a plurality of layers of woven fabric secured to the opposite end of said straps, transverse walls formed by weaving together portions of said layers so as to define a symmetrical centrally constricted opening between said layers, and a button-tab strap carried in said opening and supported by one of said defining walls.

4. In a garment-supporting device, shoulder straps, button-engaging tabs carried by one end of said shoulder straps, a plurality of layers of woven fabric of substantially identical width secured to the opposite end of said straps, transverse, symmetrically divergent opposed walls formed by weaving together portions of said layers of fabric so as to define a centrally constricted opening between said layers, and a button-tab strap carried in said opening and supported by one of said defining walls, said button-tab strap being supportable by an opposed wall when the relative position of said layers and shoulder strap is reversed.

HENRY L. JACKSON.
